UNITED STATES PATENT OFFICE

BANKS D. BROWN, OF CONNELLSVILLE, PENNSYLVANIA, ASSIGNOR TO CAPSTAN GLASS COMPANY, OF CONNELLSVILLE, PENNSYLVANIA, A CORPORATION OF DELAWARE

DESIGN FOR A TUMBLER OR SIMILAR ARTICLE

Application filed July 20, 1929. Serial No. 32,130. Term of patent 14 years.

To all whom it may concern:

Be it known that I, BANKS D. BROWN, a citizen of the United States, residing at 518 East Patterson Avenue, city of Connellsville, county of Fayette, State of Pennsylvania, have invented a new, original, and ornamental Design for a Tumbler or Similar Article of which the following is a specification, reference being had to the accompanying drawings, forming a part thereof.

Fig. 1 is a perspective view of a tumbler showing the new design; and

Fig. 2 is a bottom view of the tumbler.

The light lines in both of the figures indicate portions seen through the glass. Both the inside and the outside of the illustrative tumbler, when viewed in horizontal section, are substantially polygonal in contour.

I claim:

The ornamental design for a tumbler or similar article substantially as shown and described.

In witness whereof I have hereunto affixed my hand this 15th day of July, 1929.

BANKS D. BROWN.
